BY *Henry J. Johnson* ATTORNEY

UNITED STATES PATENT OFFICE

BERNARD O. JOHNSON, OF SONORA, CALIFORNIA

ARTIFICIAL RESPIRATOR

Application filed May 31, 1929. Serial No. 367,195.

This invention relates to first aid appliances, and particularly to one for artificially starting respiration in the lungs of one who has been subjected to and overcome by electric shocks, gases or smoke, submersion in water, and other accidents which have stopped the natural functioning of the breathing apparatus.

When a person is in this condition it is necessary to immediately start work on him to discharge the water, gases or the like from the lungs and cause fresh air to be thrown into the same in the endeavor to start the natural functioning of the respiratory organs.

The approved and most efficient method of thus applying artificial respiration is that in which the rescuer alternately presses down with his hands and releases such pressure on the back of the patient in the zone of the lungs in as closely timed sequence to the natural breathing movements or cycles of the organs as possible. These operations must be kept up unremittingly and with as even pressure and timing as possible until the desired results have been attained, or the case becomes hopeless. Since resuscitation has been effected even after the patient has been worked on for several hours it will be seen that such long continued operations are very tiring to the operator. In fact it is impossible for one operator to continue for such a period of time and it is necessary for others to relieve him at intervals.

The act of changing from one operator to another requires great care and training to accomplish effectively since any lapse in the properly timed sequence of the hand movements is apt to nullify all previous efforts. None but those properly trained in first aid work can therefore successfully carry out artificial respiration operations.

It is therefore the main object of my invention to provide a machine which may be easily operated by any person skilled or not by means of which the desired alternating pressing and relieving actions on the lungs are mechanically effected with the same pressure at all times, and with which it is very

easy to properly govern the timing of the pressing actions.

The machine is also arranged so that it may be operated by power instead of by hand, but which if operated by hand is not tiring to the operator and if it is necessary to change operators this can be easily effected without losing a stroke.

A further object is to provide an apparatus for the purpose which is of a readily portable nature so that it may be easily mounted in connection with the patient and which may be quickly adjusted to patients of different lung spacing or depth of chest; or the pressure itself easily adjusted to persons of different ages or physical builds to suit their respective conditions.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a side elevation of my improved apparatus.

Fig. 2 is an enlarged sectional elevation of the pad actuating stem unit detached.

Fig. 3 is a top plan view of the presser pads and their supporting bar.

Referring now more particularly to the characters of reference on the drawing, the apparatus comprises a rectangular frame 1 of suitable character having corner legs 1a which slidably cooperate with fixed legs 2 projecting upwardly from a flat base 3. The legs are set a sufficient distance apart so that they may straddle the body of a patient who is placed face down, as is customary, and then rests on a supporting pad 4 mounted on the base. Catch means 5 of suitable character and provided between the different pairs of cooperating legs enables the frame to be set at different distances above the base as the size of person being operated on may require.

Slidable in a bearing 6 mounted on the frame a certain distance above the base is a hollow stem 7 having a cross bar 8 on its lower end. Depending from and supported by the bar are substantially rectangular pads 9 which are shaped on their under side to substantially conform to the curvature of the back of a person in the zone of the lungs. These pads are adjustable along the bar so as to enable their spacing to be altered to conform to the spacing of the lungs of different persons.

Slidable in and projecting upwardly from the stem 7 is another stem 10 which is slidable in a bearing 11 supported by the frame some distance above the bearing 6 and vertically aligned therewith. Removably secured on the upper end of the stem 7 and on the stem 10 some distance above the stem 7 but below the bearing 11 are collars 12 between and secured to which extends a compression spring 13 which yieldably resists depression of the stem 10 in the stem 7. On the upper end of the stem 10 is a roller 14 engaged by a cam 15 mounted on a shaft 16 journaled on top of the frame 1. This cam is shaped so as to depress the stem a certain distance (which corresponds to the amount of downward movement of the hands when such are used) and to then suddenly release the same. Fixed on the shaft is a gear 17 meshing with a pinion 18 fixed on another shaft 19 which is provided on one end with a crank handle 20 for the use of the operator. In certain cases, as when the device is intended for hospital installation or to be used where electricity is readily available, a motor may be mounted on the frame and connected to the shaft 16 to drive the same. Such or any other form of operating mechanism in itself however forms no part of my invention.

In operation the frame is placed over the patient, who is positioned face down, and is set at a level such that the pads just rest on the patient in the proper position when the stem 10 is in its uppermost position. The crank is then turned, causing said stem to be depressed. This acts, through the spring 13, against the lower stem in connection with which the pads are mounted, compressing the spring somewhat and forcing the pads yieldably down in simulation of the pressure of the hands. When the cam suddenly leaves the roller 14 the pressure against the pads and also of course against the back of the patient is suddenly released and the stem 10 raises to its topmost position. This action also simulates that of the hands when their downward pressing movements are relieved. If these movements are carried out at a properly timed sequence of fifteen cycles or strokes per minute favorable results should be obtained if there is any hope at all, and it will be obvious that the operation of the device by turning the crank is much more

easily carried out even through a considerable length of time than when the hands are used. It is also much easier to shift from one operator to another if necessary to relieve the first one without losing a stroke.

To enable the proper speed of reciprocating movements or strokes to be gaged I preferably mount a small vertical and translucent cylinder 21 in connection with the frame directly below the shaft 19. A vertical auger-like element 22, driven from the shaft 19 by gearing 23 projects into a certain amount of oil or other liquid carried in the cylinder. With the rotation of the element 22 at a certain speed the level of the oil in the cylinder will be raised and when the speed is such that the shaft 16 is turning fifteen revolutions per minute the oil will then be at the level of a gage mark 24 on the cylinder. The operator thus has visual evidence of the speed of rotation of the main or cam shaft and can govern his movements accordingly.

The removability of the spring unit enables the spring to be easily interchanged for use with persons of different ages or physical builds, since it will be evident that a child or a naturally delicate or small person will not require a pressure as heavy as an adult or other person of large or normal build.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. An artificial respirator including spaced presser-pads for engagement with the back of a patient over the lungs, a vertical stem from which said pads are supported, bearing means in which said stem is slidable, another stem slidably mounted in connection with said first stem, a compression spring about and fixed at its ends in connection with the stems to force them normally apart a certain distance, and operating means arranged to intermittently engage and depress the second named stem and then suddenly release the same; the spring being compressed only when the pads are engaged with a patient and the second named stem is depressed.

2. An artificial respirator including spaced presser-pads for engagement with the back of a patient over the lungs, a vertical stem from which said pads are supported, bearing means in which said stem is slidable, another stem slidably mounted in connection with said first stem, a compression spring about

and fixed at its ends in connection with the stems to force them normally apart a certain distance, a cam positioned and shaped to intermittently depress and then suddenly release the last named stem, and means for rotating the cam.

3. An artificial respirator including spaced presser-pads for engagement with the back of a patient over the lungs, a vertical stem 10 from which said pads are supported, bearing means in which said stem is slidale, a compression spring about said stem and secured at its lower end thereto, and operating means applied to the upper end of the spring to

15

alternately compress and suddenly release the spring.

4. An artificial respirator including spaced presser-pads for engagement with the back 70 of a patient over the lungs, a horizontal bar on which said pads are adjustably mounted, a vertical stem secured to and projecting upwardly from the bar centrally of its length, a compression spring bearing down at its lower end on said stem, a vertically movable member 75 engaging the upper end of the spring, and operating means for alternately depressing and suddenly releasing said member.
